UNITED STATES PATENT OFFICE.

CHARLES R. STEVENSON, OF MISHAWAKA, INDIANA, ASSIGNOR TO NATIONAL VENEER PRODUCTS COMPANY, OF MISHAWAKA, INDIANA, A CORPORATION OF INDIANA.

PACKING-CASE.

1,177,287.

Specification of Letters Patent. Patented Mar. 28, 1916.

Application filed January 10, 1913. Serial No. 741,180.

To all whom it may concern:

Be it known that I, CHARLES R. STEVENSON, a citizen of the United States, residing at Mishawaka, in the county of St. Joseph 5 and State of Indiana, have invented certain new and useful Improvements in Packing-Cases, of which the following is a specification.

The principal object of my invention is 10 to provide a new and improved packing case that can be folded up compactly when not in use.

Another object of my invention is to provide a collapsible packing case with means 15 for quickly and easily securing its parts in operative relation or for disconnecting them so as to permit folding of the same when not in use.

These and various other objects of my 20 invention will be made apparent in the following specification and claims, taken with the accompanying drawings, in which I have illustrated one specific embodiment of my invention. It will be understood that 25 the invention is defined in the appended claims.

Referring to these drawings—Figure 1 is a perspective view of my improved device, certain parts being displaced a little from 30 their normal operative relation in order to show them more clearly. Fig. 2 is a longitudinal vertical section. Fig. 3 is a transverse vertical section. Fig. 4 is a front elevation of the device as it appears when folded. Fig. 5 is a fragmentary section on an 35 enlarged scale taken on the line 5, 5 of Fig. 3 looking in the direction of the arrows. Fig. 6 is a top plan view of the parts shown in Fig. 5. Fig. 7 is a horizontal section on the line 7, 7 of Fig. 1 looking down. Fig. 8 is a transverse section showing the 40 lower corner edges of the device in detail.

This packing case when assembled in operative condition consists of a rectangular 45 box whose walls are formed of "trunk board" or similar veneered structure. The bottom 15 is reinforced by the longitudinal wooden strips 16 and around its edges are the corner angles 17. Along the front edge 50 is an upstanding rim 18 and along the rear edge is an upstanding rim 19 of greater height, as shown in Fig. 8. At the ends are upstanding rims 20 of the same height as each other, but of greater height than 55 the rim 19.

The front wall 21 of the packing case is hinged at 22 to the upper edge of the front rim 18 so that the front wall 21 can be folded inwardly. This front wall 21 is reinforced along its upper edge by the wooden 60 strip 24 and both the upper edge of the strip 24 and the wall 21 are bound by the metal channel 23. The end edges of the front wall 21 are also bound by a similar metal channel 23. The back wall 25 is 65 hinged at 26 to the back rim 19 and is reinforced along its upper edge by the wooden strip 28 and the top and end edges of the wall 25 are bound by metal channels 27.

The end walls 29 are alike. Each end 70 wall 29 is hinged at 30 to the end rim 20 and is reinforced at the top by the strip 32, the upper edge being bound by the channel 31'. The front and rear vertical edges of the end walls 29 are reinforced by corner 75 angle strips 31 adapted to lap outside the ends of the adjacent front and rear walls 21 and 25. The reinforcing strips 32 are cut a little short at their ends so as to leave notches 33 (Fig. 6) to receive the ends of 80 the front and rear members 21 and 25. The strip 35 is hinged at 34 to the upper edge of the rear wall 25 and the cover 36 is hinged at 37 to the strip 35. This cover 36 has two hasps 38 adapted to engage the 85 respective staples 40 carried by the front member 21. Each staple 40 when not in use may be folded into the hole 39. This hole is closed on its inner side by the metal plate 41, which is riveted to the wall 21 at 90 44. This plate 41 has a clip 42 riveted at 43 which forms a pivotal support for the staple 40. The end members 29 have carrying handles 45.

Near the upper corners of the front and rear members are fastening devices, one of which is shown in detail in Figs. 5 and 6. Metal plates 46 are riveted to the front and rear members 21 and 25. This plate 46 has a lever 47 pivoted thereto at 48 and carrying a hook 49 pivoted eccentrically to the lever 47 at 50. The end of the hook is designated 51 and is adapted to engage the staple 52 carried by the corresponding end member 29.

The end members at their upper ends carry inwardly folding hasps 53 with rings 55 in their ends which may be engaged by a padlock 54 when the device is folded as in Fig. 4. When the device is assembled 110

the same padlocks can be used to fasten the hasps 38 on the staples 40.

When assembled the hooks 49 are drawn tight by means of the levers 47, thus making 5 the corners fit snugly, as shown in Fig. 6. To collapse the hamper, these hooks 49 may be loosened by means of the levers 47 and the end members 29 drop out a little, as shown in Fig. 1. Then the front member 21 can be folded 10 down flat against the bottom member 15; next the top cover 36, together with the strip 35, can be folded over on the back side of the back member 25, and then these parts can be folded down upon the previously 15 folded front member 21. This relative disposition of the parts is facilitated by the different heights of the hinges 22 and 26, as shown in Fig. 8. Finally the end members 29 can be folded down over the other 20 parts, as shown in Fig. 4, and secured by means of the locks 54. The greater height of the end rims 20 facilitates this disposition of the parts.

The walls of the hamper may be made of 25 3-ply wood veneer covered on both sides with fiber, or any other suitable material may be employed.

The hamper described herein is very rugged and firm when assembled and is so 30 constructed as to stand hard usage. When it is locked by means of the padlocks engaging the hasps 38 and staples 40, all the other fastening means are on the inside so that they cannot be reached by any meddlesome 35 person. Nevertheless the device can be very quickly and easily loosened up and folded into convenient form, as shown in Fig. 4.

I claim:

1. In a device of the class described, a bottom member, front, back and end members connected thereto, the connections comprising hinges, reinforcing strips along the inner faces of the upper edges of said members, metal channels embracing the edges of the 45 said reinforcing strips and the respective adjacent edges of the front, back and end members, and means to secure the front, back and end members in operative relation.

2. In a device of the class described, a 50 bottom member, an upstanding rim along the edge thereof, front and rear and end

members hinged thereto, reinforcing strips along the inner faces of the upper edges of said front and rear and end members, said strips on the end members being cut short 55 to permit the front and rear members and their reinforcing strips to abut against the edges of the end members, angle irons attached to those edges of the end members adjacent the front and rear members, said angle irons being adapted to receive the adjacent edges of the front and rear members and make joint with the same, and fastening means to secure the parts in operative relation.

3. In a device of the class described, a bottom member, front, rear and end members connected thereto, the connections comprising hinges, reinforcing strips along the inner faces of the upper edges of said members, metal channels embracing the edges of the 70 said reinforcing strips and the respective adjacent edges of the front, rear and end members, said reinforcing strips and channels on the end members being cut short to 75 permit the adjacent edges of the front and rear members to abut against the edges of the end members, and means to secure the front, rear and end members in operative relation.

4. In a device of the class described, a bottom member, front, rear and end members connected thereto, the connections comprising hinges, reinforcing strips along the inner faces of the upper edges of said members, metal channels embracing the edges of the 85 said reinforcing strips and the respective adjacent edges of the front, rear and end members, said reinforcing strips and channels on the end members being cut short to 90 permit the adjacent edges of the front and rear members to abut against the edges of the end members, and angle irons attached to the edges of the end members with a flange of each lapped beside the adjacent 95 edge of the respective front or rear member.

In testimony whereof, I have subscribed my name.

CHARLES R. STEVENSON.
